R. A. HEISING,
TELEGRAPH SYSTEM,
APPLICATION FILED MAY 12, 1915.

1,339,824.

Patented May 11, 1920.

UNITED STATES PATENT OFFICE.

RAYMOND A. HEISING, OF EAST ORANGE, NEW JERSEY, ASSIGNEE, BY MESNE ASSIGNMENTS, TO WESTERN ELECTRIC COMPANY, INCORPORATED, A CORPORATION OF NEW YORK.

TELEGRAPH SYSTEM.

1,339,824.

Specification of Letters Patent. Patented May 11, 1920.

Application filed May 12, 1915. Serial No. 27,527.

To all whom it may concern:

Be it known that I, RAYMOND A. HEISING, a citizen of the United States, residing at East Orange, in the county of Essex and 5 State of New Jersey, have invented certain new and useful Improvements in Telegraph Systems, of which the following is a full, clear, concise, and exact description.

This invention relates to telegraph systems and its principal object is to provide 10 an improved method and apparatus for the transmission of intelligence.

In accordance with its general characteristics the invention contemplates a transmitting device selectively and simultaneously imparting to a transmission line combinations of electric currents of different and predetermined frequencies and a receiving device controlled by the currents so imparted. More specifically, the receiving device 20 comprises a number of electro-frequency selecting systems or inductance and capacity networks, commonly called filters, responsive only to currents of frequencies within predetermined limits, converting systems for providing unidirectional currents in place of the alternating currents separated out by the respective filters and an electromagnetic selecting mechanism 25 controlled by currents from the converting systems.

The above and other objects of this invention will be fully set forth in the following description and claim, and will be 30 more readily understood by reference to the accompanying drawing wherein Figure 1 shows the circuit connections of the preferred embodiment diagrammatically, and Fig. 2 shows one method of duplexing.

The multi-frequency transmitter for selectively impressing upon a transmission line 100, various combinations of electric currents, comprises a plurality of controller switches 101, 102, 103, 104 and 105, which 40 are composed of a movable and two fixed contacts. Normally all of the movable contacts are in engagement with the lower fixed contacts. Each of these switches is adapted, when its movable contact is brought into engagement with its upper fixed contact, to 45 connect one of a plurality of current generators 111, 112, 113, 114 and 115 to the transmission line. The generators may be continuously driven at a constant speed, and 50 are so constructed and arranged that each

may impress upon the line currents of different frequencies within predetermined limits, and preferably of sine wave form, upon the operation of its corresponding switch 101 to 105 inclusive. The operation 60 of various combinations of the switches will cause the simultaneous transmission of various combinations of superimposed currents of various frequencies which may be utilized to selectively control the operation of 65 a receiver at a distant station.

The controller switches 101 to 105 inclusive may be selectively actuated by any of the usual means, such, for example, as the well-known keyboard machines wherein 70 character controlling keys are arranged in the form of an ordinary typewriter keyboard, or automatic devices whose operations are controlled by a perforated paper tape or the like.

At the receiving station where the various combinations of superimposed currents are to be translated into desired mechanical effects, such as the production of printed characters, there are located a number of 80 frequency selecting systems or electro-filtering devices 121, 122, 123, 124 and 125, there being one such filter for a given range of frequencies. Each of these filters is associated with the transmission line through a 85 suitable transformer 126 and comprises a suitable inductance 128 and a capacity 129. The inductance and capacity are so proportioned, in accordance with the well-known laws of alternating current phenomena, as 90 to respond readily to currents of particular frequencies, commonly known as the resonance frequencies, being, however, substantially unresponsive to currents of all other frequencies outside of desired or fixed 95 limits. In the embodiment of the invention shown, it will be assumed that filter 121 responds only to the impulses of generator 111, filter 122 to generator 112, etc.

Associated with each filter, preferably 100 through a suitable transformer 130, is a converting system 135 for changing the alternating current induced in the secondary of the filter into a unidirectional current suitable for controlling the actuation of a direct 105 current electromechanical device, such as a relay. These converting systems may be in the form of the well-known audion arrangement, or any suitable rectifier. In the drawing an audion arrangement is shown, 110

wherein the audion comprises a cathode 136, and anode 137 and an input electrode 138. Each of the filters 121 to 125 inclusive is therefore, associated with and may control the action of an intermediate relay 141, 142, 143, 144 and 145, respectively, whose armatures are associated with front contacts connected to a grounded source of energy 146. A source of energy 147 balances a source of energy 148 and no current passes through the corresponding relays 141 to 145 unless the audion is made active through the influence of current from transformer 130 whereupon a unidirectional current is produced. Each of relays 141 to 145 inclusive is operated by this unidirectional current supplied when its audion becomes active and causes the energization of a corresponding selector relay 1, 2, 3, 4 and 5, of a selecting mechanism, which are provided with armatures and circuit connections such that, by causing their energization in various combinations, any one of a plurality of type magnets may be energized. In accordance with this arrangement, relay 1 is provided with two armatures 11 and 12; relay 2 with three armatures 21, 22 and 23; relay 3 has five armatures 31 to 35 inclusive; while relay 4 has eight armatures 41 to 48 inclusive; and relay 5 has eleven armatures 51 to 61 inclusive. By the addition of other armatures and contacts the possible number of selections may be increased.

The type magnets are designated by the letters of the alphabet whose production they control, and may be associated with and cause the depression of the character keys of an ordinary typewriter, or may be arranged about the shaft of a rotatable type wheel to arrest it in the desired position in a manner similar to that disclosed in Patent 1,107,336, patented August 18, 1914.

A sufficient understanding of the operation of the system will be obtained from a description of the selection of a few particular characters. In order to select character A, switch 101 only of the transmitter is operated, which causes current of the frequency determined by generator 111 to traverse the transmission line. As hereinbefore mentioned, current of this frequency is incapable of influencing any of the filters of the receiver, except filter 121, which, through the agency of audion 135, causes the operative energization of intermediate relay 141. This relay pulls up its armature and completes a circuit from grounded source 146 through selector relay 1, which pulls up its armatures 11 and 12. Armature 11 completes a circuit from the negative pole of a source of energy 150 through conductor 151, winding of type magnet A, back contacts and armatures of a plurality of cut-off relays 152, 153, 154 and 155 to the other pole of source 150. Armature 12 does not com-

plete any circuit since all of the circuits controlled by it are open at armatures 22, 33, 44 and 55 of relays 2, 3, 4 and 5. Electromagnet A therefore alone receives current and is energized, and the printing of this character is effected.

The operation of switches 101 and 104 causes the simultaneous transmission of currents of frequencies determined by generators 111 and 114. These currents cause a responsive action in none of the filters at the receiving station, except 121 and 124, through whose associated audions 135 intermediate relays 141 and 144 are operatively energized. The attraction of the armatures of relays 141 and 144 completes circuits from grounded source 146 through the corresponding selector relays 1 and 4 which pull up their armatures 11-12 and 41 to 48. Armatures 12 and 44 complete a circuit from the negative pole of source 150 through conductor 160, winding of type magnet H, winding of cut-off relay 152, back contacts and armatures of cut-off relays 153, 154 and 155 to the opposite terminal of source 150. Armature 11 completes the previously traced circuit through type magnet A to the back contact of cut-off relay 152, and armature 41 completes a circuit from source 150 through conductor 161 and the winding of type magnet D also to the back contact of this relay. Cutoff relay 152, however, is receiving current from the previously traced circuit through type magnet H, and since it is more rapid in its operation than any of the type magnets, the circuits through type magnets A and D are opened at the armature of this relay before they are sufficiently energized to cause them to perform their functions. Relay H therefore alone is energized, since a study of the drawing will show that none of the other armatures of relay 4 complete energizing circuits, and character H will be reproduced by the printing mechanism.

The operation of switch 105 alone causes the transmission of a current of a frequency to cause the operation of selector relay 5, which pulls up its armatures 51 to 61 inclusive. The only armature which completes a circuit is armature 51, which establishes a circuit from source 150 through conductor 162 and type magnet E, through the back contacts and armatures of cut-off relays 152, 153, 154 and 155 to the other pole of source 150, which results in the energization of type magnet E and the production of this character.

The operation of any three of the switches 101 to 105 inclusive will result in the energization of a combination of three of the selector relays 1 to 5 inclusive with the resultant attraction of their armatures. Because, however, of the fact that some of the circuits partly prepared by these attracted

armatures are open at the armatures of some of the other selector relays, or are opened before the type magnets therein can be energized because of the more rapid operation 5 of the cut-off relays 152 to 155 inclusive, only one type magnet will be energized sufficiently to cause it to effect the printing of its corresponding character. For convenience in determining the combinations of 10 impulses required to select any particular type magnet, these magnets have been arranged in groups, according to the number of impulses required to select any type magnet therein. Thus the first group is made 15 up of type magnets A to E inclusive, which are selected by one frequency currents; the second group comprising magnets F to O inclusive are selected by two frequency currents; type magnets P to U inclusive require 20 three frequencies for their selection, while type magnets V, W and X require four frequencies and type magnet Y requires five.

It will thus be apparent that by selectively closing switches 101 to 105 inclusive in various combinations, resulting in the energization 25 of the corresponding selector relays 1 to 5 inclusive, any of the type magnets may be energized to cause the production of the corresponding type.

This system may be duplexed in the ordinary manner by connecting the apparatus at each end in accordance with Fig. 2. The transmitter is connected by conductor 158 to the midpoint of an inductive resistance 30 157, one terminal of which is connected to an artificial line AL, the other terminal being connected to line 100. The transformers 126 will be joined between the terminals of resistance 157 as indicated.

With this system, two messages may be simultaneously transmitted and received at opposite ends of the line without duplexing by associating with the transmission line at the station where the switches 101 to 105 40 are located a set of frequency selecting systems similar to filters 121 to 125 inclusive, whose induction and capacity are so proportioned that they are unresponsive to any of the currents controlled by generators 111 to 45 115 inclusive. These filters may, through the agency of suitable converting systems and electro-responsive devices, control the actuation of selecting mechanism such as

that already described. At the receiving station where filters 121 to 125 inclusive are 55 located, the transmission line would be associated with a suitable transmitter provided with switches and generators controlling the application of currents of frequencies to which filters 121 to 125 inclusive do not respond, but which cause a response in the corresponding filters at the station where switches 101 to 105 inclusive are situated. With this arrangement, the simultaneous 60 application of currents of different frequencies at the opposite ends of the line will have no effect upon the home station, but will cause the selective operation of the apparatus at the distant station without 65 interference.

The capacity of the system may be further increased by providing additional sets of apparatus for transmitting and responsive to different sets of frequencies at either or each end of the line whereby two or more 70 sets of signals may be simultaneously worked in the same direction.

The invention claimed is:

A system of communication comprising in combination with a line conductor, a plurality of constantly operating alternating current generators, each generator adapted to produce a frequency or range of frequencies different from that produced by any of the other generators, means for connecting said 80 generators to said line in characteristic combinations, depending upon the signal to be transmitted, a receiving system connected to said conductor comprising a plurality of selective networks, each network having capacity and inductance so adjusted as to permit the passage of the current frequencies transmitted by a corresponding one of said generators, but to offer a substantial 85 limiting impedance to currents of other frequencies, a vacuum tube rectifier individual to each of said networks having its input circuit connected to said network, an electromagnetic operation-controlling device in the output circuit of each of said amplifiers, and 90 a printer selecting mechanism under the joint control of said operation-controlling devices.

In witness whereof, I hereunto subscribe my name this 11th day of May, A. D. 1915. 105
RAYMOND A. HEISING.
